ATTORNEY.

UNITED STATES PATENT OFFICE.

HARRY H. BROWN, OF DULUTH, MINNESOTA.

TURNSTILE.

1,294,763.

Specification of Letters Patent. Patented Feb. 18, 1919.

Application filed August 3, 1918. Serial No. 248,121.

To all whom it may concern:

Be it known that I, HARRY H. BROWN, a citizen of the United States, residing at Duluth, in the county of St. Louis and State of Minnesota, have invented certain new and useful Improvements in Turnstiles, of which the following is a specification, reference being had therein to the accompanying drawing.

10 This invention relates to turnstiles and has special reference to a turnstile used in the making of payments or deposits of money by employees to their employer's cashier's office such, for example as a street car company's office.

However, there are other places where the handling of money or other valuables is necessary in which the invention could be used to advantage.

20 At the cashier's office of a street car company where many such deposits of money are made daily, it is quite common to have the cashier held up and robbed, and to avoid the possibility of this, is the primary object 25 of my present invention.

Another object is to provide certain novel features of convenience for facilitating the turning in of deposits such as above referred to.

30 Still other objects and advantages of the invention will appear during the further description thereof.

Referring to the accompanying drawings, forming part of this application, and in 35 which similar reference characters represent like parts:

Figure 1. is a horizontal sectional view through one of the improved turnstiles.

Fig. 2. is an elevation of the entrance and 40 exit side of the turnstile.

Fig. 3 is a top plan view of the pawl and ratchet wheel arrangement at the top of the stile, and

45 Fig. 4. is an enlarged fragmental view of portions of the pawl and ratchet wheel operating device.

1 represents the receiving cashier's counter in a room adjacent the wall 2 of a building having an offset or jog in it, as indicated at 50 3, such construction being a true representation of the plan of one of the turnstiles now in successful operation, it being understood that with different surrounding conditions the construction may be considerably modified without departing from the spirit of the invention.

In the front wall 4 of the cashier's room and above his counter 1 is formed the usual receiving opening or window 5, which communicates with the substantially semicircular housing of the turnstile which comprises the sections 6 and 7.

Within the housing 6—7 is pivotally mounted in any suitable manner, upon the vertical shaft 8, the turnstile which comprises three radially disposed solid wooden or other suitable wings 9, they being spaced equidistant apart, and of such proportion in relation to their surrounding walls as to but one occur at any time intermediate of the outer end of the wall section 6 and the wall 2 in such a manner as to permit either entrance or exit to or from the turnstile.

Behind the wall 4 and adjacent the wall 2, in plain sight of the cashier as he stands naturally at his work at the counter, is formed an opening 10 having a mirror 11 placed at an angle therein, in such a manner as to reflect the image of a person entering the turnstile to the cashier, there being an opening 12 formed in the wall section 7 for such purpose. By this arrangement the cashier may readily see at all times just who may be entering the turnstile.

Upon the outer face of each wing 9 of the turnstile is permanently mounted a small shelf 13 for the convenience of the person entering the turnstile and to be used by him in carrying his tray containing the deposit he is about to make. One of these trays is indicated at 14 on the larger shelf 15, fixed to the wing 2 adjacent the entrance to the turnstile.

A number of these trays or containers 14 are supplied on the shelf 15 for use by the depositors and in practice are generally returned to the shelf by each depositor after having made his deposit with the cashier.

This arrangement of shelves and plurality of trays is found in practice to be a great 100 convenience where a large number of depositors use the turnstile at or about the same time.

On the top of the turnstile and supported by the wings 9 thereof is securely fixed the 105 ratchet ring wheel 16 having a series of notches 17 formed in its inner circumferential edge, engaged by a suitable spring pawl 18 to prevent the turnstile being rotated backwardly, which is common in such devices, and a series of oppositely disposed notches 19 formed in its outer edge, engaged

5 by the pawl 20. This latter pawl is controlled by any suitable connection of rods and bell cranked levers 21, 22, 23, 24, 25, 26, and 27 to the pivotally mounted pedal on foot lever 28, upon the floor 29 under the cashier's counter. This connection is so made that the weight of the pedal normally holds the pawl 20 in engagement with the notches 19, and the turnstile cannot be operated until the pedal 28 is depressed by an operator in the cashier's compartment. The pawls 18 and 20 are pivotally carried upon the underside of an angle plate 30, fixed to the wall 4, and above the plate 30 is fixed 10 the V shaped metal bracket 31, which forms a bearing support for the upper end of the turnstile shaft.

15 It is obvious that all of the controlling mechanism of the turnstile shall be covered in some suitable manner to make it inaccessible to any one outside of the cashier's room.

20 By this arrangement it is evident that any one entering the turnstile and operating 25 it to a point where his return backward is impossible, his exit therefrom is wholly controlled by the operator in the cashier's room and that a second depositor entering the following compartment may be seen by the 20 cashier at the same time the first depositor is in front of him.

Having thus described my invention, what

I claim as new and desire to secure by Letters Patent, is:—

1. The combination with a depositor's 35 turnstile of the character described comprising a plurality of vertically disposed radial wings and a stationary working shelf adjacent the entrance to the turnstile, of a laterally projecting shelf fixed to one side of 40 each wing whereby objects prepared for deposit, upon the stationary shelf may be carried upon one of the laterally projecting shelves by the depositor while in the turnstile. 45

2. The combination with a room having a receiving window therein and a partially inclosed turnstile adjacent the window having opaque wings thereon, and controlled from within the room, of means whereby a 50 second party in the turnstile following the first party may be seen from within the room.

3. The combination with a cashier's turnstile of the character described having 55 opaque wings therein, of reflecting means whereby a party entering the turnstile may be seen from the cashier's desk.

In testimony whereof I hereunto affix my signature in the presence of two witnesses 60

HARRY H. BROWN.
